MAKING A TRANSFER TAIL

John T. Rich, Morristown, Tenn., assignor to American Enka Corporation, Enka, N. C., a corporation of Delaware

Application August 20, 1953, Serial No. 375,401

7 Claims. (Cl. 57—34)

This invention relates to thread collection and more particularly to the collection of a continuously running thread on a twisting machine.

With the advent of continuous spinning, numerous problems have presented themselves in connection with the collection of the continuously issuing threads. The take-up used in such a process must be provided with a means for disposing of the running threads during the doffing operation. When desirable, such a take-up must also be provided with a means for producing a magazine wrap or transfer tail on the bobbins used to collect the thread.

It has heretofore been proposed to utilize, on a thread take-up for a continuous process, a bobbin characterized by having one slotted flange between the ends of the core on which the thread is wound. The tail or end of the thread is then maintained wholly outside of the thread package. For example, see U. S. Patent 2,431,323. While the use of such a specially constructed bobbin has been found to have certain advantages, it has been observed that the loose end of the transfer tail tends to be swung outwardly by centrifugal force during the winding operation and become damaged or dirty. Also, the length of transfer tails produced in such an operation varies considerably from one bobbin to another, and this is undesirable.

It is an object of the present invention to provide a method and apparatus for doffing a twisting machine.

Another object of the invention is to provide a method and apparatus for producing a transfer tail on a bobbin used to collect thread produced in a continuous manner.

A further object of the invention is to provide a method and apparatus for producing transfer tails of substantially uniform length on the bobbins used for collecting continuously produced threads.

Other objects will appear from the following descriptions when taken in conjunction with the annexed drawings wherein:

Figure 1 is a schematic perspective of a single position on a ring twisting machine modified in accordance with a preferred embodiment of the present invention;

Figure 2 is a schematic perspective similar to Figure 1 showing a bobbin in place on the twister spindle;

Figure 3 is a sectional view taken along the central axis of the bobbin used in the present invention;

Figure 4 is a perspective view of a special tail confining sleeve used in the present invention;

Figure 5 is a plan view of a special thread cutter used in the present invention; and

Figure 6 is a view in part elevation of the cutter shown in Figure 5.

In accordance with the present invention, a tail confining sleeve is attached to the ring twister, concentrically surrounding the spindle at the base of the bobbin. An extension on the bottom of the bobbin which contains the transfer tail fits inside this sleeve. In this manner the transfer tail is maintained within the sleeve in a clean and undamaged condition as the twisting operation proceeds. By the use of a pneumatic collection device and a special thread cutter in combination with the tail con-

2

fining sleeve, clean undamaged transfer tails of substantially uniform length are produced.

Referring now to Figures 1 and 2, a continuously running thread 10 passes through guide 11 mounted over spindle 12 on a ring twister. Spindle 12 is driven by suitable means (not shown). During the doffing operation, as shown in Figure 1, the thread 10 is taken up by means of a pneumatic thread-suction collection device schematically illustrated at 13. Collection device 13 may be of any suitable design, such as the one described in Application Serial No. 237,526, filed July 19, 1951 now U. S. Patent No. 2,661,588. Disposed in the thread path between collection device 13 and spindle 12 is a thread cutter schematically indicated at 14.

Cutter 14, the details of which are shown more clearly in Figures 5 and 6, comprises an L-shaped supporting member 15 having mounted thereon a thin resilient metal cutting blade 16. The cutting edge of the blade 16 is indicated at 19. Cutting blade 16 is held in place by screw 17 which passes through a slot in blade 16 to the wall of supporting member 15. As shown by dotted lines in Figure 6, a portion of the supporting member 15 is cut away to provide an opening through which the thread can pass to the cutting edge 19.

It will be seen from Figure 5 that the cutting edge 19 normally lies barely in contact with shoulder 18 of supporting member 15. With a thread running through the device from the top of the drawing toward the bottom of the drawing in Figure 5, blade 16, which is movable at its unsupported end, tends away from shoulder 18 and the passage of the thread through the device is not hindered. However, if the direction of thread travel is reversed and the thread begins to travel through the device from the bottom of the drawing to the top of the drawing in Figure 5, cutting edge 19 is immediately drawn by the friction of the running thread into contact with shoulder 18 and the thread is severed at once. Thus it is seen that in the arrangement shown in Figure 1 the cutter 14 permits thread 10 to continue to pass to collection device 13 but as soon as an attempt is made to reverse the direction of thread travel and withdraw the thread 10 from the collection device 13 toward the twister spindle 12 the thread is severed. The cutter 14 per se is not part of the present invention; such a device is well known in the textile industry and may be commercially obtained.

As seen more clearly in Figure 3, the bobbin used in the present invention comprises a central hollow core portion 20, a lower flange 21 and an upper flange 22. At the top of the bobbin is a gripping knob 23. As seen in Figure 2, lower flange 21 contains a slot 24 which extends from the periphery of the flange to core portion 20 of the bobbin.

The under side of flange 21 is provided with a relatively thick rim 22. Concentrically disposed on the under side of lower flange 21 is hub portion 26. Hub portion 26 contains a shallow groove 25 around its periphery adapted to carry a transfer tail.

Referring now to Figure 4, there is shown cylindrical metal sleeve member 30. Extending from the top of sleeve 30 for a short distance along the wall is an angular slot 31. The lower edge of sleeve 30 is provided with horizontal extension members 32, 33 containing apertures 34, 35 by means of which sleeve 30 may be attached around the base of the spindle to the ring rail of the twisting machine.

It will be apparent that when sleeve 30 is mounted around twister spindle 12 in the position shown in Figure 1, the lower portion of the spindle 12 will be concentrically enveloped by the sleeve 30. More specifically, the major portion of hub portion 26 of the bobbin will be enveloped by sleeve 30 when the bobbin is in

place on the spindle 12. The opening through which the thread is drawn into collection device 13 is disposed in a horizontal plane not higher than the lowest part of the slot 31 in sleeve 30. Preferably the collection device 13 is disposed slightly beneath the lowest part of slot 31 to hold the running thread in the slot.

When the bobbin is placed on the spindle 12 as shown in Figure 2, the upper portion of sleeve 30 extends up into the annular recess formed between rim portion 22 and hub portion 26 of the bobbin flange 21. With the bobbin in place on the spindle, the lowest part of the slot 31 is disposed opposite the groove 25 on hub portion 26. In this manner the groove 25 adapted to contain the transfer tail is closely surrounded by sleeve 30 and the transfer tail is accordingly confined to a small area and maintained clean and undamaged. If it happens that the tail escapes the confining sleeve 30 it will nevertheless be contained to a certain extent by the rim 22 on the lower side of flange 21.

Bearing in mind the foregoing description of the various parts of the present apparatus, an explanation will now be given of a typical doffing operation. When a bobbin has been filled and is ready to be doffed, the spindle is stopped, the running thread is severed and taken immediately to temporary collecting device 13. The thread may then be placed in cutter 14. The filled bobbin is then removed as shown in Figure 1. During this time the running thread continues to be collected by collection device 13. If it should become necessary to thread the running thread through the ring again the procedure set forth in U. S. Patent 2,572,138 may be used.

In order to build a transfer tail and start the thread on an empty bobbin the following procedure is followed. The thread running to the temporary collecting device 13 is threaded through the traveler 36. With the thread running in this position a fresh bobbin is placed on the spindle and the running thread is slipped into the slot 24 in the bottom flange of the bobbin. The bobbin is then rotated slightly manually so as to cause the slot 24 to pass back and forth over the slot 31 in sleeve 30. This results in the thread being caught in slot 31. The path of thread travel at this stage of the operation is as follows: through pigtail 11, traveler 36, slot 24, slot 31, cutter 14, to collecting device 13.

Rotation of the spindle 12 is then commenced. When this occurs, two things happen: (1) the oncoming thread immediately starts to build up on the core portion 20 of the bobbin, and (2) the thread is severed by the cutter 14. As the spindle continues to rotate, the loose end is withdrawn from the cutter 14 through the slot 31 in sleeve 30 into the interior of the sleeve 30 where it is wound onto groove 25 to form the transfer tail.

By suitably arranging the cutter 14 so that it is always spaced the same distance from spindle 12, transfer tails of uniform length will be produced on all bobbins. Each spindle on the twisting machine may be provided with a cutter-collection device assembly or optionally one such assembly may be used to service a number of spindles by moving the assembly from one spindle to another as the doffing operation proceeds.

It is to be understood that various modifications might be made in the foregoing description without departing from the spirit of my invention.

What is claimed is:

1. In a ring twister for winding yarn on a flanged bobbin a barrel of which has an extension thereon the combination of a spindle, a cylindrical sleeve disposed coaxially around the base of said spindle and adapted to surround a tail-containing portion of said extension, said sleeve having a slit in the wall thereof and means capable of exerting a yarn drawing action in a horizontal plane not higher than said slit.

2. In a ring spinning device for winding continuously produced yarn on a flanged bobbin the barrel of which has an extension thereon the combination of a spindle,

a cylindrical sleeve disposed coaxially around the base of said spindle and adapted to surround a tail-containing portion of said extension, said sleeve having a slit in the wall thereof, a temporary collection device capable of exerting a drawing action in a horizontal plane not higher than said slit and a thread cutter in the thread path between said slit and said temporary collection device.

3. In a ring spinning device for winding continuously produced yarn on a flanged bobbin the barrel of which has an extension thereon the combination of a spindle, a cylindrical sleeve mounted coaxially around the base of said spindle and adapted to surround a tail-containing portion of said extension, said sleeve having a slit in the wall thereof, a temporary collection device capable of exerting a drawing action in a horizontal plane not higher than said slit and a thread cutter in the thread path between said slit and said temporary collection device.

4. In a ring spinning device for winding continuously produced yarn on a flanged bobbin the barrel of which has an extension thereon the combination of a spindle, a cylindrical sleeve mounted coaxially around the base of said spindle and adapted to surround a tail-containing portion of said extension, said sleeve having an angular slit in the wall thereof, a temporary collection device capable of exerting a drawing action in a horizontal plane beneath said slit and a thread cutter in the thread path between said slit and said temporary collection device.

5. In a ring spinning device for winding continuously produced yarn on a flanged bobbin the barrel of which has an extension thereon the combination of a spindle, a cylindrical sleeve mounted coaxially around the base of said spindle and adapted to surround a tail-containing portion of said extension, said sleeve having an angular slit in a portion of the wall thereof, a temporary collection device capable of exerting a drawing action in a horizontal plane not higher than said slit and a thread cutter in the thread path between said slit and said temporary collection device.

6. In a ring spinning device for winding continuously produced yarn on a flanged bobbin the barrel of which has an extension thereon the combination of a spindle, a cylindrical sleeve mounted coaxially around the base of said spindle and adapted to surround a tail-containing portion of said extension, said sleeve having an angular slit in a portion of the wall thereof, a temporary pneumatic collection device capable of exerting a drawing action in a horizontal plane not higher than said slit and a thread cutter in the thread path between said slit and said temporary collection device.

7. In a ring spinning device for winding continuously produced yarn on a flanged bobbin the barrel of which has an extension thereon the combination of a spindle, a cylindrical sleeve mounted coaxially around the base of said spindle and adapted to surround a tail-containing portion of said extension, said sleeve having an angular slit in a portion of the upper wall, a temporary pneumatic collection device capable of exerting a drawing action in a horizontal plane beneath said slit and a thread cutter in the thread path between said slit and said temporary collection device, said thread cutter being so constructed that the thread is instantaneously severed when an attempt is made to withdraw the running thread from the temporary collection device toward said slit.
